UNITED STATES PATENT OFFICE.

WALTER H. CRAMER, OF DALLAS, TEXAS.

STEEL FORM FOR LAYING CONCRETE.

1,202,269.

Specification of Letters Patent. Patented Oct. 24, 1916.

Application filed February 24, 1916. Serial No. 80,298.

To all whom it may concern:

Be it known that I, WALTER H. CRAMER, a citizen of the United States, residing at Dallas, in the county of Dallas and State of Texas, have invented certain new and useful Improvements in Steel Forms for Laying Concrete, of which the following is a specification.

My invention has relation to an improvement in metal forms for use in the laying of concrete side-walks, curbs and gutters, and in such connection it relates more particularly to the arrangement and construction of such forms whereby the parts of the same may be readily separated for transportation and readjustment and readily assembled and reassembled for use.

In the carrying out of my invention I provide longitudinal metal strips or rails in the preferred form of channel iron, the base of the channel pieces constituting a face form for the concrete and these rails or strips are formed with meeting ends arranged to interlock not only with each other and with an inclosing strip but to interlock with and properly support a dividing templet. Where side walks are to be constructed the rails are laid in pairs with the dividing templets serving also to separate the rails the required distance and in addition to the templets the two rails are connected by metal straps. In curb or gutter construction three rails are provided of varying depths and interlocked end to end to each other and to the anchors and steel dividing templets. Straps and channel bars, readily detachable from connected parts, serve to maintain the intermediate rail in proper position with respect to the outer and inner rails.

The nature and scope of my invention will be more fully understood from the following description taken in connection with the accompanying drawings, forming part hereof, in which,—

Figure 1 is a perspective view of a metal form for constructing side-walks, said form embodying the main features of my invention; Fig. 2, is a side elevational view of the meeting and interlocking ends of the side rails of the form; Fig. 3, is a perspective view of the parts of Fig. 2 separated from each other; Fig. 4, is a perspective view of one of the radius rails for use with the forms; Fig. 5, is a perspective view of a metal form for constructing curbs and gut-

ters, said form also embodying the main features of my invention; Fig. 6, is a cross-sectional view of the form illustrated in Fig. 5; Fig. 7, is a detail perspective view of the interlocking parts of the form; and Fig. 8, is a detail perspective view of one of the supporting channel braces of the form.

Referring to the drawings and particularly to Figs. 1 to 4 thereof in which the form embodying my invention is devised for use in the laying of concrete side walks, the side rails or longitudinal strips 1, 1, of the form consist of ordinary channel iron and each strip is divided into preferably two sections 1^a, 1^b, the ends of a strip of each section interlocking with an anchor 2. Inasmuch as the means for interlocking the two ends of adjacent sections 1^a, 1^b, to each other through the intermediary of a plate 2 constituting an anchor for the rails is one of the essential features of my invention I will proceed to describe these means in detail. Referring more particularly to Fig. 3 of the drawings, the anchor plate 2 has an upper flanged edge 3 and vertically cut notch 4. One side edge of anchor plate 2 is also provided with a recess 5. In assembling the parts together the anchor plate 2 is inserted in the channel section 1^a with its top flange 3 resting under the top flange 6 of the rail section 1^a. The recess 5 of plate 2 enters and interlocks with a recess 7 cut longitudinally in the lower flange rail section 1^a. The contiguous connecting end of rail section 1^b has its top flange bent downward as at 8 and this vertical flange 8 is recessed or notched as at 9 to interlock in the notch 4 of anchor plate 2. When the two rails are to be maintained in parallel relationship as shown in Fig. 1, a dividing templet 10 spans the two rails and is secured to the opposite anchor plates 2. To permit of an interlocking of the ends of the templet 10 with the top edge of the anchor plates the ends of templet 10 are each notched as at 11 to fit into a notch 4 of an anchor plate 2. The extreme ends of templet 10 project some distance beyond the rails 1 to furnish hand holds in the removal of the templet. When required straps 12 may be provided to still further connect the rails 1 together and prevent their spreading or buckling. To more or less permanently secure the anchor plate 2 to the rails a bolt 13 and nut 14 may be used.

In Fig. 4 the construction is illustrated

when applied to a radius rail 15. Radius rail 15 in this instance is preferably provided with an additional anchor plate 16, removably secured to the inner surface of said rail by nut and bolt 17.

In Figs. 5 to 8 the construction is illustrated when applied to curb and gutter construction. In this instance the inner rail 21 and the outer rail 22, both of channel iron but of varying depths, correspond otherwise to rails 1 of the side walk form. Each rail 21 and 22 is made in interlocking sections with anchor plates precisely as are rails 1 of the other construction. In addition to these rails 21 and 22 there is provided an intermediate rail 23, between which and rail 22 a space is formed for the reception of the material forming the curb. The rail 23 is supported above the ground A (see Fig. 6) and in proper position by the channel braces 24 securing the base of rail 23 to the top of rail 21 and by the straps 25 connecting the top flanges of all three rails together. The intermediate rail 23 is connected up in sections by a slightly different construction from that used in connecting up rails 1, rails 21, or 22. Each section of rail 23 is provided with ears 26 extending beyond the free edges of the sections on the inside of the rail. When the sections are in position to clamp the dividing templet 27 these ears of adjacent sections overlap and are interlocked with the edge of templet 27.

Having thus described the nature and objects of my invention, what I claim as new and desire to secure by Letters Patent is,—

1. In a form for laying concrete, a rail formed in a plurality of sections from channel iron or its equivalent, an anchor plate and means for interlocking the contiguous ends of meeting sections to said anchor plate.

2. In a form for laying concrete, a rail formed in a plurality of sections from channel iron or its equivalent, an anchor plate, a dividing templet, and means for interlocking the ends of contiguous sections and the dividing templet to said anchor plate. 45

3. In a form for laying concrete, two parallel flanged rails each divided into a plurality of abutting sections, an anchor plate for each rail interlocked with the ends of the abutting sections and a dividing templet spanning the space between the parallel rails and interlocked at each end with the respective anchor plates for the rails. 50

4. In a form for laying concrete, two parallel flanged rails each divided into a plurality of abutting sections, an anchor plate for each rail interlocked with the ends of the abutting sections and a dividing templet spanning the space between the parallel rails and interlocked at each end 65 with the respective anchor plates for the rails, in combination with an intermediate rail, braces extending from the flange of one of the exterior rails to the base of said intermediate rail and arranged to support 70 said intermediate rail, and straps securing the flanges of the parallel rails to the upper flange of the intermediate rail.

5. In a form for laying concrete, two parallel flanged rails each divided into a plurality of sections formed from channel iron or its equivalent, an anchor plate and means for interlocking the contiguous ends of meeting sections to said anchor plate, in combination with a radius rail arranged to 75 80 be interlocked to the anchor plates of the channel iron rails.

In testimony whereof I have signed my name to this specification.

WALTER H. CRAMER.
